ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

LOCKING CABINET DOOR

Application filed November 26, 1929. Serial No. 409,772.

This invention relates generally to a locking door structure particularly useful in cabinets for visible index trays. In accordance with the invention it is proposed to 5 mount a door at the front of the cabinet and hingedly support it at its lower edge so that when released the door may be swung forwardly and downwardly into a horizontal position in which, if desired, it may then be 10 slid rearwardly into the cabinet along ways provided for that purpose. When in closed position the door is latched by a spring-pressed keeper which may be retracted by a finger pull. A lock is mounted at the lower 15 portion of the cabinet in operative relation to the latch so that the tumbler may be thrown into its path and prevent its retraction so as to lock the door.

Another object of the invention is to provide in a door of the character described a 20 detent which shall extend from its upper edge to its lower edge and form a reenforcing element therefor.

Other features of the invention will be 25 described in greater detail hereinafter in connection with the description of the embodiment shown in the accompanying drawings, in which:

Figure 1 is a view in front elevation of the 30 improved cabinet showing the door in vertical closed position and indicating relationship between the lock and the detent.

Figure 2 is a view partly in side elevation and partly in section of the cabinet shown in 35 Figure 1.

Figure 3 is a fragmentary detailed view 40 in section taken on the plane indicated by the line 3—3 of Figure 1 and looking in the direction of the arrows, the bolt of the lock being engaged with the detent to lock the door.

Figure 4 is a view similar to Figure 3 showing the relation of parts when the bolt of the lock is retracted but the detent engaged for latching the door.

Figure 5 is a view similar to Figure 4 but showing the detent retracted to release the door.

Figure 6 is a fragmentary view partly in 50 side elevation and partly in section showing

the door when fully opened and also indicating in dotted lines how it may be slid into the cabinet when in horizontal position.

Figure 7 is a detailed view in transverse section through the cabinet taken on the 55 plane indicated by the line 7—7 of Figure 4 and looking in the direction of the arrows and showing the supporting pintles for the door.

The cabinet illustrated in the drawings is 60 formed of sheet metal and it is in such constructions that the improvements will find their greatest usefulness. This cabinet, which is completely enclosed except for the front, accommodates a bank of horizontally 65 disposed trays *a* such as may be suitable, for instance, for visible index cards. The front of the cabinet is closed by a vertically disposed door *b*. In the opposite edges of this door near the bottom are mounted 70 laterally extending pintle pins *c* one or both of which may be pressed outwardly by springs *c'* which may facilitate assembly and disassembly of the parts. These oppositely extending pins *c* when the door is in 75 lowered position may engage suitable guide flanges *d* on the jamb forming the opening of the cabinet, thus holding the door in proper relation to the cabinet at all times.

When the door is swung forwardly and 80 downwardly to a horizontal position, as indicated in dotted lines in Figure 6, it is in

such relation to a space *e* incorporated in the cabinet as to permit it to be slid rearwardly into the cabinet to a greater or less 85 extent.

When in this position the protruding part of the door is, of course, very firmly supported and may itself serve as a shelf or support for the trays *a* within the cabinet or any other objects.

When in vertical position, as illustrated in Figures 3, 4 and 5, the door rests on its bottom edge directly on the base of the cabinet. In this position it is desirable to provide a detent by which the door may be releasably retained in position 90 and also a lock to secure the contents of the cabinet. In the improved construction the door is shown as formed with a peripheral frame *b'*. Slidably engaged with the upper and lower rails of this frame is a 95

100

vertically disposed detent f . This rod in the relationship illustrated constitutes a reinforcing element for the framing aside from serving the additional functions described below. Its upper end indicated at f' , which may be beveled, is adapted to enter an opening g provided in the frame of the cabinet. To the detent f is secured a finger pull g' which is disposed adjacent the upper edge of the door and this finger pull may be moved downwardly to disengage the upper end f' of the detent from the opening g so as to permit the door to be dropped and opened. The lower end of the detent f is supported on a spring h of any suitable character but shown as a leaf spring disposed within the lower hollow rail of the door frame. Retraction of the detent f by the finger pull g' is opposed yieldingly by the spring h which normally urges the detent in latching engagement with the opening g . Upward movement of the detent f is limited by a shoulder f^2 formed thereon. The retracted position of the latch is illustrated in Figure 5.

Within the base of the cabinet on the inner front wall is secured the case of a lock k of any suitable character, the key slot k' being presented at the front wall of the cabinet below the door. The bolt k^2 of this lock is illustrated in Figures 1 and 3 as protruded while in the other views it is illustrated as retracted. Since the assembly is such that it is preferred that the bolt shall not engage the lower end of the detent f directly a loose plunger l is shown as mounted within the lower hollow rail of the door frame and disposed normally in line with the lower end of the detent f and the bolt k^2 . The plunger l may be secured conveniently to a leaf spring m also secured within the lower hollow rail of the door frame, this spring serving to urge the plunger towards the bolt normally, as illustrated clearly in Figure 7. When the bolt is protruded it engages the lower end of the plunger l and forces it upwardly until the spring m is in juxtaposition to the spring h . When the parts are in this position it is evident that the detent f cannot be moved downwardly by operation of the finger pull g' and necessarily remains engaged with the opening g . The door is thus locked until such time as a key is inserted in the slot k' and the bolt of the lock retracted to permit the plunger l to move away from the lower end of the detent f .

The entire construction is rugged, simple to manufacture, easy to assemble, pleasing in appearance and affords convenient operation of the door and the detent and lock mechanism during normal use. Changes within the range of mechanical skill may obviously be made without departing from

the spirit of the invention, the scope of which is defined by the appended claims.

What I claim is:

1. The combination of a vertically disposed door hinged along its lower edge to a jamb, a vertically disposed slidable detent extending between the upper and lower edges of the door and normally engaging the jamb adjacent the upper edge of the door, a spring engaging the detent to oppose its retraction yieldingly and a lock mounted in the jamb with its bolt movable into cooperative relation with the lower end of the detent to prevent positively its retraction. 75

2. A door jamb, a door having a frame formed as a hollow rail extending around its perimeter, a vertically disposed slidable detent extending between the upper and lower rails of the door, a spring within the lower rail engaging the lower end of the detent, a plunger mounted in the lower rail in line with the lower end of the detent, a spring to urge the plunger normally away from the lower end of the detent and a lock mounted on the jamb and having a bolt movable into engagement with the plunger to urge it into the path of movement of the lower end of the detent to prevent its retraction. 80 85

3. A door jamb, a door having a frame formed as a hollow rail extending around its perimeter, a vertically disposed slidable detent extending between the upper and lower rails of the door, a spring within the lower rail engaging the lower end of the detent, a finger pull supported on the upper rail of the door and engaged with the detent to permit its retraction, a plunger mounted in the lower rail in line with the lower end of the detent, a spring to urge the plunger normally away from the lower end of the detent and a lock mounted on the jamb and having a bolt movable into engagement with the plunger to urge it into the path of movement of the lower end of the detent to prevent its retraction. 90 95 100 105 110

This specification signed this 19th day of November, A. D. 1929.

ROLAND A. FURLONG.
